G. L. FOGLER

BURNER

Filed April 8, 1921

FIG. 1

FIG. 2

FIG. 3

INVENTOR

George L. Fogler,
By Kay, Totten & Brown,
Attorneys

UNITED STATES PATENT OFFICE.

GEORGE L. FOGLER, OF PITTSBURGH, PENNSYLVANIA, ASSIGNOR TO JAMES B. BLACK-BURN, OF PITTSBURGH, PENNSYLVANIA.

BURNER.

Application filed April 8, 1921. Serial No. 459,763.

To all whom it may concern:

Be it known that I, GEORGE L. FOGLER, a citizen of the United States, and resident of Pittsburgh, in the county of Allegheny and State of Pennsylvania, have invented a new and useful Improvement in Burners; and I do hereby declare the following to be a full, clear, and exact description thereof.

10 My invention relates to burners for liquid, gaseous or colloidal fuels, and it has for its object to provide an improved burner construction wherein the fuel and air are more thoroughly mixed than in any type of 15 burner heretofore known.

More specifically, one object of my invention is to provide a burner having a mixing chamber and means for conducting a stream of air into the mixing chamber 20 and for injecting a stream of fuel against, and in the opposite direction to, the incoming stream of air. The fuel, when it first enters the mixing chamber, thus moves directly away from the combustion point, its 25 movement being checked by the moving stream of air and the fuel being thus caused to "mushroom" or spread in all directions. By this means, the fuel is thoroughly broken up and mixed with the air, and is 30 carried in suspension in the air to the point of combustion.

Another object of my invention is to provide means for imparting a rotary movement to a combustion mixture of air and 35 fuel immediately before the mixture is introduced into the combustion chamber, thereby agitating the fuel and air and mixing them still more thoroughly.

In hydrocarbon burners of the so-called 40 "injector type" a stream of air under pressure is caused to move across or around a fuel inlet opening, the fuel being either drawn into the mixing chamber by the suction effect of the current of air or being 45 forced into the mixing chamber under pressure. In either case the fuel has heretofore been introduced into the mixing chamber while moving either in the same direction as the stream of air or in a direction. 50 across the path of movement of the air. The oil or gas so mixed with the air is broken up to a greater or less extent and is carried with the air into the combustion chamber, but in every case the individual 55 particles of the fuel are still relatively large

when they reach the point of combustion, since they travel mainly in the same direction as the air and are therefore not subjected to disintegrating forces. The result is that when the mixture enters the combustion chamber there is not sufficient air in contact with the individual particles of fuel to completely burn the fuel unless a very large excess of air is employed, in which case a considerable part of the heat produced by the combustion of the fuel is absorbed by the excess of air and the heat-efficiency of the fuel is thus reduced.

According to my present invention I employ an entirely novel method of mixing the fuel with the air in the mixing chamber of the burner, whereby the fuel, instead of being merely brought into contact with the stream of air, is driven directly against the stream of air. This method of feeding the fuel in counter-current relation to the incoming current of air has the advantage that the mechanical impact of the two oppositely moving streams serves to break up the fuel very thoroughly and distribute it 70 intimately with the air in the mixing chamber, so that the fuel arrives at the combustion point in homogeneous mixture with the air and not as a mass of relatively large globules as in ordinary burners. Therefore, without using a great excess of air 75 there is sufficient oxygen present to burn the fuel completely and quickly.

The air and fuel are still more thoroughly mixed, just before they enter the combustion chamber, by means of a deflector which imparts to the mixture a rotary motion around the axis of its onward movement, the rate of onward movement being at the same time somewhat checked in order to 90 obtain better dispersion of the mixture in the combustion chamber.

For a further understanding of my invention reference may now be had to the accompanying drawing, in which Fig. 1 is 100 a vertical central sectional view showing somewhat diagrammatically a simple form of burner constructed in accordance with my invention; Fig. 2 is a transverse sectional view through the deflector portion of 105 the burner of Fig. 1, the section being taken substantially on the line 2-2, Fig. 1; and Fig. 3 is another transverse sectional view of the deflector, the section being taken substantially along the line 3-3, Fig. 1. 110

In the drawing, the numeral 1 indicates in a general way the breast wall of a furnace or other combustion apparatus composed of suitable refractory material and 2 5 indicates one of the usual burner tiles having a flaring opening 3 through which mixed fuel and air are delivered into the furnace through a burner of my improved construction, having as its main parts an 10 air inlet 4, a fuel inlet 5, a mixing chamber 6 and a deflector or agitator 7.

The mixing chamber 6 and the air inlet 4 may consist, as shown, of a single tubular member 8 provided with a damper 9 for 15 regulating the admission of air through the inlet 4. The fuel inlet 5, as shown, consists of a pipe extending through the wall of the tubular member 8 and having a nozzle portion 5^a which is bent at right angles to the 20 inlet pipe 5 and lies substantially in the axis of the tubular member 8. The fuel nozzle 5^a has a reduced discharge opening 10. A valve 11, of any suitable construction, regulates the admission of fuel through the 25 inlet member 5 and is connected by means of a pipe 12 to any suitable source of liquid or gaseous fuel, not shown, the fuel being preferably supplied under suitable pump pressure or gravity pressure sufficient to 30 cause the fuel to issue from the discharge opening 10 of the nozzle 5^a in a stream having considerable velocity. The air is also supplied under pressure, but the pressure of the air should be somewhat less than the 35 pressure under which the fuel is delivered in order that the air pressure may not shut off the flow of fuel.

The upper end of the tubular member 8 is threaded to receive a flange 13 which 40 supports the deflector 7. For this purpose the flange 13 is provided with openings 14 to receive bolts 15 which extend through similar openings in lugs 16 that extend laterally from the lower end of a sleeve 17 which 45 encloses the deflector. The upper end of the sleeve 17 fits into a recess 18 adjacent to the flaring opening 3 which leads into the combustion chamber.

A gasket 19 of suitable packing material 50 is clamped between the flange 13 and the deflector sleeve 17 by means of nuts 20 applied to the bolts 15.

The sleeve 17 is provided at its lower edge with screw threads 21 into which is 55 screwed a flange 22 formed at the lower edge of a hollow conical deflector member 23. The deflector member 23 is provided with a number of slots 24 extending from the flange 22 nearly to the top of the deflector and 60 shorter slots 25 are disposed between the long slots 24. The slots 24 and 25 are inclined laterally, as best shown in Figs. 2 and 3, so that the mixture of fuel and air passing through these slots is given a side- 65 wise deflection and a rotary movement is

thus set up in the fuel and air mixture. The combined areas of the slots 24 and 25 should be substantially equal to the area of the inlet to the deflector, and this inlet area should be substantially equal to the area of the upper end of the sleeve 17, where it joins the flaring opening 3.

The cross-sectional area of the annular space around the cone 23 should be equal, at all points, to the area of the inlet and 75 outlet of the deflector. The combustion mixture thus meets with but little resistance in passing through the deflector, its movement being merely changed, in part, from simple forward movement to rotation around the 80 axis of its forward movement.

The mixture of air and fuel issuing through the longer slots forms a hollow whirling cone which is more or less independent of the hollow cone of air and fuel issuing through the shorter slots, and these two bodies of material act upon each other to increase the homogeneity of the air and fuel mixture. In order to increase this effect still further, the shorter slots may be set 85 at an angle different from that of the longer slots, or may be inclined in the opposite direction.

In certain cases, as where very heavy fuel oil is burned, two or more deflectors may be 90 employed in tandem, the fuel and air mixture passing through the deflectors successively before entering the combustion chamber.

In operation, air enters the burner under 95 constant pressure, through the inlet 4, and oil, gas or other liquid, semi-liquid, colloidal or gaseous fuel, which may be pre-heated if desired, enters through the inlet 5 controlled by the valve 11 and issues from the discharge opening 10 directly against the incoming stream of air. The fuel is thus broken up thoroughly, and the intimate mixture of air and fuel so produced is carried on by the air pressure existing in the mixing 100 chamber and passes through the slots 24 and 25 in the deflector member 23, being thereby given a spinning movement around its axis 105 of forward movement in the manner described above. At this time the speed of 110 onward movement of the fuel and air mixture is reduced, by reason of the flaring shape of the opening 3, and the combustion mixture spreads laterally from the opening 115 3 instead of issuing in a solid stream. When the mixture enters the combustion chamber, the air and fuel are so thoroughly mixed 120 that the fuel burns completely without forced draft, and develops its maximum thermal efficiency.

The two main features of my invention 125 which I consider to be novel and important are, first, the mixing of fuel with air by driving the fuel against an advancing stream of air and in the opposite direction,

thus producing absorption of the fuel in the air while in suspension therein, and second, the additional mixing of the air and fuel by agitating the mixture just before it enters the combustion chamber.

Either of these two principal features of my invention may be used alone, if desired, the counter-current mixer being used without the deflector, or the deflector being attached to some other form of mixer. For best results, however, the mixer and the deflector should both be employed. The deflector has certain independent uses. For example it may be introduced into the fuel intake of an internal combustion engine, between the carburetor and the intake manifold, where it greatly improves the combustion by producing a more intimate and homogeneous mixture of fuel and air.

My counter-current mixing device also has certain independent uses, such for example, as the stripping of gases containing heavier vapors or liquids. In particular, this part of my invention is of great advantage in separating gasoline from natural gas, according to the method set forth and claimed in my copending application for Letters Patent filed April 8, 1921, Serial Number 459,764.

It will be understood that the burner need not be arranged vertically as shown in the accompanying drawing, but may be installed with the mixing chamber horizontal or otherwise arranged, according to the circumstances where it is to be used. It will also be understood that my invention is not restricted to the use of any particular kind of fuel, or to any particular kind of heating apparatus, being equally applicable to furnaces, stationary boilers, locomotive boilers, marine boilers, and to all other uses where effective combustion of fluid fuel is desired. As applied to marine boilers, my burner has the advantage that the boiler room need not be kept under super-atmospheric pressure, as is the case in ordinary oil burning ships' boilers, for the reason that the air supply is delivered directly from the blower to my burner in a closed channel, instead of being drawn into the burner from the boiler-room, as is ordinarily the case on oil-burning vessels. Where a number of burners are supplied with air from the same blower, a header is connected to the blower and is provided with branch pipes leading to the individual burners. This arrangement also prevents back-firing, which frequently occurs in boiler rooms where the air is drawn into the burners directly from the room.

The structural details herein shown and described may be varied in many respects without departing from my invention, and I therefore desire that the construction here

shown be taken as merely illustrative and that no limitations be imposed on my invention except such as are indicated in the appended claims.

I claim as my invention:

1. A burner comprising a mixing chamber, means for introducing a stream of air into the said chamber, means for introducing a stream of fluid fuel under pressure into the said mixing chamber and in a direction opposite to the direction of movement of the air, said mixing chamber being substantially unobstructed to the said fuel inlet, and means for agitating the resulting mixture of air and fuel between the said mixing chamber and the point of combustion. 70

2. A burner comprising a mixing chamber, means for introducing a stream of air into the said chamber, means for introducing a stream of fluid fuel under pressure into the said mixing chamber and in a direction opposite to the direction of movement of the air, said mixing chamber being substantially unobstructed to the said fuel inlet, and means for imparting a rotary movement to the resulting mixture of air and fuel between the said mixing chamber and the point of combustion. 85

3. A burner comprising a tubular mixing chamber, a damper disposed at the air inlet thereof, a fuel inlet extending through one wall of the said mixing chamber and having a nozzle extending axially of the said chamber and toward the said damper, and a deflector secured to the end of the said tubular member opposite the said damper, the said deflector comprising a sleeve or casing and a hollow conical member disposed within the said sleeve and having slots formed lengthwise along its sides, the said slots being inclined laterally so as to impart a rotary motion to the combustion mixture issuing through the said slots from the said tubular member. 90

4. A burner comprising a mixing chamber, means for supplying fuel and air to the said chamber, a deflector, an inlet from the said mixing chamber to the said deflector and an outlet from the said deflector, the said deflector having openings formed therein for the passage of the mixed fuel and air, the combined areas of the said openings being substantially equal to the area of the said inlet and being also substantially equal to the area of the said outlet. 110

5. A burner comprising a mixing chamber, means for supplying fuel and air to the said chamber, a deflector comprising a hollow cone having its larger end in communication with the said mixing chamber and having a plurality of laterally inclined slots formed lengthwise along its sides, and a sleeve surrounding the said cone and 125

spaced therefrom, the combined areas of the said slots being substantially equal to the area of the inlet end of the said cone and being also substantially equal to the outlet from the said sleeve.

6. A burner comprising a mixing chamber consisting of a straight cylinder, means for admitting air axially into the said chamber, a fuel inlet extending through one wall of said chamber and having a nozzle extending axially to said chamber and open-

ing in the direction opposite to that of air-flow through said chamber, the said mixing chamber being unobstructed except for said fuel inlet and nozzle. ¹⁶

In testimony whereof, I, the said GEORGE L. FOGLER have hereunto set my hand.

GEORGE L. FOGLER.
